Patented July 12, 1927.

1,635,800

UNITED STATES PATENT OFFICE.

FRANCIS G. OKIE, OF PHILADELPHIA, PENNSYLVANIA, ASSIGNOR TO MINNESOTA
MINING & MANUFACTURING COMPANY, OF ST. PAUL, MINNESOTA, A CORPORATION
OF MINNESOTA.

COMPOSITE STRUCTURE.

No Drawing.

Application filed March 4, 1922. Serial No. 541,248.

My present invention relates in general to the treatment of material, preferably in sheet form, and more particularly the treatment of material for the purpose of forming or attaining composite structures, of which well known forms of abrasives such as what is commonly known as sand-paper is an example.

This application is a continuation in part 10 of my applications, Serial Numbers 428,287 and 428,289.

Although I hereinafter disclose the practice of my invention in connection with abrasives such as sand-paper, it will be understood that my invention, or certain features, 15 thereof, have a wider field of utility.

Composite structures of the abrasive type such as sand-paper or emery cloth comprise generally (a) a base of sheet material, which 20 may be felted as in the case of paper or woven as in the case of cloth, (b) a more or less finely comminuted resistant material having abrading properties, such as garnet or corundum, and (c) a binder generally in 25 the form of a glue which serves to bind the abrasive to the base.

The abrasive products as produced at present have as incidents certain features among which are (1) defect of desired drying qualities, (2) affinity for moisture rendering them substantially inutile in the presence of water or moisture, (3) the tendency to premature pulverization or disintegration of the binder when exposed to normal atmospheric conditions and other undesired drying qualities, and (4) cracking, with consequent exposure of the base, when bent.

The principal objects of my present invention are the provision of a binder which functions more efficiently than any known to me; the provision of a binder characterized by flexibility without cracking or other undesirable effect; the provision of a binder

45 characterized by extensibility and compressibility to accommodate itself to flexion of the base; the provision of a binder by means of which the desired adhesive action between it and the base is attained not only 50 efficiently but also with a desirable degree of acceleration, and more particularly the provision of a binder in which the drying

action will be effective from the contact surface between it and the base outwardly; the provision of a binder in which the drying action will be effective from the outer surface inwardly; the provision of a binder characterized by a drying action that permits of handling the product with a minimum of delay and more particularly such 60 handling without impairment of the superficies of the material; the provision of a binder characterized by an accelerated drying action; the provision of a binder characterized by a limitation of its drying action; the provision of an improved moisture-proofing treatment for material, and especially material in a sheet form, and more particularly for causing a moisture proofing agent to penetrate into the material to an 70 extent short of exudation on an adjacent surface thereof; the provision of a moisture-proof composite abrasive structure; the provision of a binder having moisture-proofing functions, and the provision generally of 75 an improved composite abrasive structure and of a method of producing the same, together with such other objects and additional benefits and advantages as may herein-after appear or be pointed out.

In the employment of my present invention for the production of sand-paper and the like (which I cite for purposes of example) I use as the base such a sheet of material (which may be paper) as will conveniently serve the employment contemplated, and as the abrasive such comminuted material (which may be crushed garnet) similarly adapted to serve the function in view.

It is desirable that the binder utilized 80 have the functions and characteristics not only of great mechanical strength and of great binding strength, but also that it be non-hygrosopic, permeative, moisture-resistant, easily worked, readily obtainable, 85 inexpensive and facilely applied.

I have discovered that gums of such types as are used in the manufacture of the better grades of varnish are peculiarly adapted for the attainment of these ends and that gums 100 such as kauri, copal, dammar are examples of these types. Gum dammar is preferred by me as best attaining the desired ends, viewed from certain aspects.

In preparing the binder for use, the gum is used in connection with a suitable vehicle which I prefer is of a type such as linseed oil or china wood oil, for reason which I will proceed to explain.

In applying a gum prepared with a vehicle such as linseed oil to one surface of a base of paper for example I have found that the action of the vehicle involves a penetration of the base by the vehicle, for example linseed oil, to a point which approximates the opposite surface of the sheet but falls short of actual exudation of the vehicle upon such opposite surface.

10 This results in a moisture-proofing of the material even against the absorption of moisture through the surface opposite to that to which the binder is applied, without at the same time defacing or otherwise undesirably affecting such opposite surface.

This penetration by the vehicle, particularly when coupled with the use of the character of gum pointed out above, carries with it in such penetration a certain amount of 25 finely divided gum so that a coating and binding action is secured between the fibres or elemental portions of the base which thus substantially retards, if it does not entirely prevent, disintegration of the material of 30 the base, in addition to preventing access of moisture through the base to the plane of contact between the base and the main mass of the binder material.

35 The efficient action of the binder may be enhanced in the manufacture of sand-paper if the binder is applied to the base by the use of pressure and the more or less finely divided abrasive is then applied in such a manner as to cause it to adhere to the binder.

40 In order to accelerate the adhesion between the binder and the base, I have discovered it desirable to use with the binder a modifying agent the action of which is to cause a desiccation of the binder initiated at 45 the contact surface of the binder with the base and effective outwardly.

In my experience I have discovered that there are a number of materials having a metallic base which are useful for my present purposes, that manganese oxides are peculiarly useful and that borate of manganese best combines siccative energy with the desirable susceptibility to fine grinding.

50 Due to the relatively slow drying of binders generally, difficulties are encountered in handling the structure, within a convenient period because of the soft and sticky character particularly of the exposed surfaces of the binder. This objection I mitigate by associating with the improved binder a substance the action of which is to produce an accelerated drying action effective primarily at the exposed surface and working inwardly, and for this purpose I incorporate 55 in the binder a modifying element peculiarly

effective in its action as an oxidizing agent on such vehicles as linseed oil and as a retarding agent with reference to the excess absorption of the vehicle by the base.

The substance I have discovered to be particularly adapted for this purpose is that carbonate of lead or white lead known to the trade as Dowdy White which is a new electrolytic process white lead and which in my experience is found to be more satisfactory than any other known form of carbonate of lead.

Whereas by itself the Dowdy White adds but relatively little strength to the binder, in association in the binder with the borate of manganese it intensifies the action of the binder in holding the abrasive firmly against the base.

For intensifying the binding action of the binder and for intensifying the drying action of the dryers, and at the same time accomplishing such ends by the employment of a material which is efficacious in holding the mineral elements in suspension without loss of siccative energy or reducing the relative fluidity of the material, I have discovered that it is advantageous to employ as part of the binder a paste dryer. This may comprise such mineral substances as sugar of lead and borate of manganese suspended in a resinous vehicle but I find it preferable to form the paste dryer so as to have the minerals contained therein in the form of acetate of lead and resinate of manganese. I have found by experience that the paste 100 dryer should be somewhat in the nature of cheesy butter, rather softer, and of a light brownish grey color.

As an auxiliary in (1) accentuating the adhesion of the binder to the paper, (2) facilitating to a certain extent the spreading of the binder, and (3) modifying as desired the consistency of the binder as is useful in cases where it is desired to render it more fluid, I have discovered that the use of a 105 japan dryer is desirable. Such a dryer as that known as Schrack japan, owing to its relative freedom from resin, is preferable. One form of this contains shellac, red lead, litharge, manganese oxid, burnt umber, gum, 110 linseed oil, and turpentine q.s.

In order to give the binder the desired body volumetrically considered I preferably employ a varnish consisting largely of linseed oil boiled until it reaches nearly a solid 115 state. As far as feasible this should be as free as possible from glycerides and fatty acids.

The aforementioned gums, such as gum dammar are preferably employed in the 125 form of a varnish which is substantially three parts Batavia Dammar, steam kettle melted, with two parts kettle boiled linseed oil.

While gum copal and gum kauri in cer- 130

tain respects make more substantial binders than gum dammar, as they will carry more oil and dry harder under certain conditions as may be useful for certain purposes, generally speaking the present relatively greater expense does not ordinarily justify their use for most purposes, which are well served by gum dammar.

Though I have hereinabove disclosed certain forms of useful dryers having various characteristics, and likewise intensifiers, I have discovered that where it is advisable that the siccative action thereof be limited, or at least retarded, under certain conditions, or when producing material for certain purposes, that it is desirable to incorporate in the binder a non-drying oil such as castor oil or the like, for such purposes.

Sand-paper made in accordance with the disclosure of my present invention is characterized by great flexibility without any adverse effects, such as cracking of the binder or base, or loosening of one from the other: and great resistance to water, and moisture generally.

Due to the character of binder for sand-paper and the like which I thus produce, the adhesion between the base, binder and abrasive is such that an auxiliary bonding material, such as the outermost or top sizing coat, customarily found necessary, may for some purposes be dispensed with but may be applied for other purposes. Additionally, the nature of the bond between the base binder and abrasive is such that sand-paper produced according to my present invention is characterized by freedom from clogging when used on varnished and analogous surfaces.

The materials used by me as hereinabove described may be varied in character so as to vary the characteristics of the binder from the stand-point of adhesiveness, non-hygroscopy, and flexibility. Where such variation in the use of materials is employed to produce, for instance, increased adhesion between the binder and the abrasive, such increase may be attained, though possibly at a certain expense of its characteristic of flexibility.

Due, however, to this very same increased adhesiveness, one or more of the outer layers of the base may be removed as by the employment of a base which involves the use of a built up structure having a number of plies, certain of which may be removed, or by shaving off part of the thickness of the base.

By this process I am enabled to obtain sand-paper characterized by extraordinary thinness and flexibility, in that I am able to form sand-paper and the like with a base so thin that such product could not be manufactured, if the base originally used were of the thinness ultimately desired.

Having thus described my invention and illustrated its use, what I claim as new and desire to secure by Letters Patent is:

1. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent, whereby to form an abrasive article which is flexible, moisture-proof and tenacious when dry. 80

2. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent and causing a limitation of the penetration of the binder into said sheet, whereby to form an abrasive article which is flexible, moisture-proof and tenacious when dry. 90

3. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent, and causing desiccation of the binder to be accelerated outwardly, that is, from the surface thereof in contact with the sheet, whereby to form an abrasive article which is flexible, moisture-proof and tenacious when dry. 105

4. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent and causing desiccation of the binder to be accelerated both at the surface thereof exposed to the atmosphere and at the surface which is in contact with the sheet, whereby to form an abrasive article which is flexible, moisture-proof and tenacious when dry. 120

5. The process for making sandpaper or the like which includes as steps thereof the employment of a flexible sheet of fabric, causing a moisture-proofing material to serve as a vehicle for a binding agent, ap- 130

- plying said moisture-proofing material and agent as a coating to the sheet, applying a grit to said coating and allowing the vehicle to penetrate the sheet and carry with it a portion of the binding agent and causing an intensification and limitation of the desiccation of the binder by the use of modifying agents, one of which is adapted to accelerate drying and the other of which is adapted to limit drying, whereby to form an abrasive article which is flexible, moisture-proof and tenacious when dry.
6. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent, and regulating the thickness of the binding coating and limiting the degree of penetration of the sheet by the binder to prevent starving of the bond between the grit and said sheet, whereby to form an abrasive article which is flexible, moisture-proof and tenacious when dry.
7. The new process of forming a new article of manufacture in the nature of sandpaper which includes employing a suitable base, applying to said base a binder layer characterized by flexibility, tenacity in the presence of moisture and friction, and causing said binder to penetrate into the base for moisture-proofing the latter and for rendering the connection between the binder and the base durable and limiting the penetration of said binder into said base.
8. The new process of forming a new article of manufacture in the nature of sandpaper, which includes employing a suitable base, applying to said base a binder layer characterized by flexibility and tenacity in the presence of moisture and friction, applying pressure for causing said binder to penetrate into the base for moisture-proofing the latter and for rendering the connection between the binder and the base durable, applying a layer of grit to said binder and limiting the penetration of the base by said binder.
9. The process for making sandpaper or the like which includes as steps thereof the employment of a flexible sheet of fabric, causing a moisture-proofing material to serve as a vehicle for a binding agent, applying said moisture-proofing material and agent as a coating to the sheet, applying a grit to said coating and allowing the vehicle to penetrate the sheet and carry with it a portion of the binding agent, and causing desiccation of the binder to be accelerated inwardly, that is, from the surface thereof in contact with the air, whereby to form an abrasive article which is flexible, moisture-proof and tenacious when dry.

In testimony whereof I have hereunto signed my name.

FRANCIS G. OKIE.
